Primary Examiner — Sandra Snapp*Assistant Examiner* — Wendy Arminio(74) Attorney, Agent, or Firm — Leanne Taveggia Farrell; Westman, Champlin & Koehler, P.A.(57) CLAIM

The ornamental design for an industrial filter, as shown and described.

DESCRIPTION

FIG. 1 is a perspective view of an industrial filter showing my new design;

FIG. 2 is a front view thereof, the back view and the side views being identical;

FIG. 3 is a top view thereof; and,

FIG. 4 is a bottom view thereof.

The broken lines shown in the drawings are included for purposes of illustrating portions of the industrial filter and form no part of the claimed design.
